DESIGN FOR A COMBINED WASHING MACHINE AND WRINGER

Kent C. Haven, Syracuse, N. Y., assignor to Easy
Washing Machine Corporation, Syracuse, N. Y.,
a corporation of Delaware

Application November 22, 1937, Serial No. 73,095

Term of patent 7 years

To whom it may concern:

Be it known that I, Kent C. Haven, a citizen of the United States of America, residing in the city of Syracuse, county of Onondaga, and State of New York, have invented a new, original, and ornamental Design for a Combined Washing Machine and Wringer, of which the following is a specification, reference being had to the accompanying drawings, forming part thereof.

Figure 1 is a side perspective view of a com-

bined washing machine and wringer showing my new design; and

Figure 2 is a top perspective view thereof.

Figure 3 is a view of the machine shown in Figure 1 taken from the opposite side.

I claim:

The ornamental design for a combined washing machine and wringer, substantially as shown.

KENT C. HAVEN.
